UNITED STATES PATENT OFFICE.

JOHN M. JOHNSON, OF KANSAS CITY, MISSOURI.

SWIVEL COUPLING.

Application filed December 28, 1923. Serial No. 683,157.

To all whom it may concern:

Be it known that I, JOHN M. JOHNSON, a citizen of the United States, residing at Kansas City, in the county of Jackson and State of Missouri, have invented certain new and useful Improvements in Swivel Couplings, of which the following is a specification.

My invention relates to swivel couplings and my object is to provide a device of this character whereby circuit wires and various electrical appliances, such for instance, as telephone transmitters and receivers, electric lamps, etc., may be connected without twisting the associate wires.

Other objects will hereinafter appear, and in order that the invention may be fully understood, reference will now be had to the accompanying drawing, in which:

- 20 Fig. 1 is an elevation of the device.
Fig. 2 is an enlarged vertical section on line II—II of Fig. 1.
Fig. 3 is a cross section on line III—III of Fig. 2.
25 Fig. 4 is a cross section on line IV—IV of Fig. 2.

In carrying out the invention, I employ an inner conductor 2 provided at one end with a terminal 4 having suitable means such as a binding screw 6 whereby a circuit wire A may be connected to said terminal 4. A portion of the inner conductor 2 is surrounded by an insulator 8 upon which a tubular conductor 10 is mounted, having one end abutting a shoulder 12 on said insulator 8. The tubular conductor 10 is provided at one end with a terminal 14 having suitable means such as a binding screw 16 whereby a circuit wire B may be connected to said terminal 14.

40 18 designates a second tubular conductor free to rotate upon and having one end abutting an annular shoulder 20 on the tubular conductor 10. The tubular conductor 18 is separated from the inner conductor 2 by an insulator 22, against which a metallic plate 24 abuts.

The inner conductor 2 extends through the plate 24 and is provided at one end with a collar 26 between which and said plate 24 a coil spring 28 is interposed. The spring 28 presses upwardly on the plates 24 and downwardly upon the collar 26 and thus yieldably holds the tubular conductor 18 against the shoulder 20 of the tubular conductor 10 to insure a good contact between

said tubular conductors and at the same time permit them to rotate independently of each other.

30 designates a metallic cap connected to the metallic plate 24 and surrounding the spring 28, the collar 26 and the associate end of the inner conductor 2. The cap 30 is provided with a pole 32 which extends through one end of an insulator plug 34 enclosing the tubular conductor 18, the insulator 22, the metallic plate 24 and said cap 30. The lower portion of the insulator plug 34 is sheathed in a screw threaded conductor 36 which is in circuit with the tubular conductor 18 through the intermediacy of a conductor 38.

40 designates a shell, preferably, of insulating material threaded upon the upper end of the plug 34 and provided at its upper end with an opening 42 through which the wires A and B extend.

With the parts constructed and arranged as above described it is apparent that when the plug 34 is rotated to screw it into a socket (not shown) that the tubular conductor 18 will rotate upon the tubular conductor 10, thereby permitting the latter with its terminal 14 and the inner conductor 2 with its terminal 4 to remain stationary, so that the wires A and B will not become twisted as would be the case if said terminals 14 and 4 should rotate with the plug 34.

When the plug 34 is screwed into a lamp socket and the wires A and B are connected to an electrical appliance, such, for instance, as a motor, the current will pass from one pole of said socket through the conductors 36, 38, 18 and 10, terminal 14, circuit wire B, the motor not shown, and return to the socket, not shown, through the circuit wire A, terminal 4, inner conductor 2, plate 24, cap 30 and pole 32.

From the foregoing description it is apparent that I have provided a coupling embodying the advantages above pointed out, and while I have shown and described the preferred construction, combination and arrangement of parts I reserve the right to make such changes as properly fall within the spirit and scope of the invention as claimed.

Having thus described my invention, what I claim and desire to secure by Letters Patent, is:

1. In a device of the character described an inner conductor adapted to be connected

to a circuit wire, a tubular conductor insulated from but extending around the inner conductor and adapted to be connected to a circuit wire, a second tubular conductor rotatably connected to the first tubular conductor and abutting a shoulder thereon, an insulator separating said second tubular conductor and the inner conductor, a metallic plate mounted on the inner conductor and bearing against said insulator, and spring means embracing the inner conductor and bearing against said metallic plate to yieldably hold the second tubular conductor in engagement with the shoulder of the first conductor.

2. In a device of the character described an inner conductor adapted to be connected to a circuit wire, a tubular conductor insulated from but extending around the inner conductor and adapted to be connected to a circuit wire, a second tubular conductor rotatably connected to the first tubular conductor and abutting a shoulder thereon, an insulator separating said second tubular conductor and the inner conductor, a metallic plate mounted on the inner conductor and bearing against said insulator, spring means embracing the inner conductor and bearing against said metallic plate to yieldably hold the second tubular conductor in engagement with the shoulder of the first conductor, and a metallic cap connected to said metallic plate and embracing said spring means and provided with a pole.

3. A device of the character described consisting of an inner conductor, an insulator surrounding said conductor, a tubular conductor surrounding said insulator and having a shoulder, a second tubular conductor rotatably connected to the first tubular conductor and abutting the shoulder thereon, an insulator interposed between the inner con-

ductor and said second conductor, spring means whereby the second tubular conductor is yieldably held in engagement with the shoulder of the first tubular conductor, an insulator screw plug connected to the second tubular conductor, a metallic threaded shell fixed to said screw plug and in circuit with the second tubular conductor, and a pole extending through the insulator screw plug and in circuit with the inner conductor.

4. A device of the character described consisting of an inner conductor, an insulator surrounding said conductor, a tubular conductor surrounding said insulator and having a shoulder, a second tubular conductor rotatably connected to the first tubular conductor and abutting the shoulder thereon an insulator interposed between the inner conductor and said second conductor, spring means whereby the second tubular conductor is yieldably held in engagement with the shoulder of the first tubular conductor, an insulator screw plug connected to the second tubular conductor, a metallic threaded shell fixed to said screw plug and in circuit with the second tubular conductor, a pole extending through the insulator screw plug and in circuit with the inner conductor, terminals on the adjacent ends of the inner conductor and first tubular conductor, means for securing circuit wires to said terminals, and a shell removably connected to the screw plug and enclosing said terminals and provided with an opening through which the circuit wires may extend.

In testimony whereof I affix my signature, in the presence of two witnesses.

JOHN M. JOHNSON.
